(57) CLAIM

The ornamental design for a decorative cover for a diaper receptacle, as shown and described.

DESCRIPTION

FIG. 1 is a perspective view of a decorative cover for a diaper receptacle showing my new design.

FIG. 2 is a side view of the decorative cover for a diaper receptacle of FIG. 1.

FIG. 3 is a bottom view of the decorative cover for a diaper receptacle of FIG. 1; and,

FIG. 4 is a top view of the decorative cover for a diaper receptacle of FIG. 1.

The dashed lines show a diaper receptacle and form no part of my design.
